DISPLAY PACKAGE FOR CIRCULAR CUTTING BLADES OR THE LIKE

Lasher F. Arthur, Haddam, Conn., assignor to Robert T. Reynolds, doing business as Robert T. Reynolds Associates, Newington, Conn.

Filed Aug. 20, 1970, Ser. No. 24,594

Term of patent 14 years

Int. Cl. D9—99

U.S. Cl. D9—191

FIG. 1

FIG. 2

FIG. 3

FIG. 6

FIG. 4

FIG. 5

FIG. 1 is a front elevation of a display package for circular cutting blades or the like showing my new design;

FIG. 2 is a bottom view thereof;

FIG. 3 is a top view thereof;

FIG. 4 is a rear elevation thereof;

FIG. 5 is a side elevation as seen from the right of FIG. 1; and

FIG. 6 is a side elevation as seen from the left of FIG. 1.

I claim:

The ornamental design for a display package for circular cutting blades or the like, as shown.
